[57] CLAIM

The ornamental design for a tape dispenser, as shown and described.

DESCRIPTION

FIG. 1 is a perspective view from the front right side of a tape dispenser according to the present invention;
FIG. 2 is a perspective view taken from the back left side of the tape dispenser according to the present invention;
FIG. 3 is an elevational view of a back of the tape dispenser according to the present invention;
FIG. 4 is an elevational view of the right side of the tape dispenser according to the present invention;
FIG. 5 is a front elevational view of the tape dispenser according to the present invention;
FIG. 6 is a bottom plan view of the tape dispenser according to the present invention;
FIG. 7 is a side elevational view of the left side of the tape dispenser which has been rotated through 90° from the view of FIG. 4;
FIG. 8 is a top plan view of the tape dispenser according to the present invention;
FIG. 9 is a perspective view of the right part showing the inside of the tape dispenser according to the present invention; and
FIG. 10 is a perspective view of the left part of the tape dispenser according to the present invention.
